UNITED STATES PATENT OFFICE.

WILLIAM J. BURT, OF OKLAHOMA, OKLAHOMA, ASSIGNOR TO OKLAHOMA PAPER COMPANY, A CORPORATION OF OKLAHOMA.

PAPER BOX.

1,163,209.

Specification of Letters Patent.

Patented Dec. 7, 1915.

Application filed July 10, 1915. Serial No. 39,097.

To all whom it may concern:

Be it known that I, WILLIAM J. BURT, a citizen of the United States of America, a resident of Oklahoma city, in the county of Oklahoma, State of Oklahoma, have invented certain new and useful Improvements in Paper Boxes, of which the following is a full, clear, and exact description, reference being had to the accompanying drawings, forming a part of this specification.

My invention relates to improvements in paper boxes, the main object being to produce a strong and simple paper box.

Prior to this invention, foldable paper boxes such as suit boxes, have been so formed that they have not been amply reinforced by their own paper elements; and it has been found necessary, or desirable, to reinforce the end walls of such boxes by folding the upper edges of said end walls, and then inserting separate reinforcing elements in said folded upper edges.

An object of my invention is to produce a paper box of this kind having its end walls so formed that they constitute a series of reinforcing elements which amply reinforce the box structure. In combination with these reinforcing elements I produce a fastening flap which is so formed that it secures the series of reinforcing elements in its folded condition.

Figure I is a plan view of a paper box blank, embodying the features of my invention. Fig. II is a plan view of a portion of the box blank, showing its end wall member as it appears immediately before the final operation of folding the reinforcing elements. Fig. III is a plan view of a portion of the box as it appears after the different wall sections and reinforcing elements have been folded. Fig. IV is a transverse section, showing the box as it appears immediately before the reinforcing elements have been folded into the box. Fig. V is a view similar to Fig. IV, showing the reinforcing elements folded into the box and secured thereto. Fig. VI is an enlarged section on line VI—VI Fig. II. Fig. VII is an enlarged section taken on line VII—VII, Fig. V. Fig. VIII is an enlarged section taken on line VIII—VIII, Fig. V. Fig. IX is a plan view of the foldable box as it appears when all of its elements are secured

together, the box being shown in its "knock down" condition.

A designates a bottom wall or body member.

B designates side wall members, and C designates end wall members.

The box blank is scored on the lines 1 and 2 (Fig. I) so that the side and end wall members may be folded on these lines. Each side wall member is provided with extensions 3 having diagonal scores 4. Each side wall member B is also scored at 2' to permit the extensions 3 to be folded, as will be hereinafter described. Each end wall section C is extended and preferably scored to produce reinforcing elements 5, 6 and 7, each of which is adapted to extend across the box. The extended portion of each end wall member is also slotted at 8 and 9 to produce a fastening flap 10. The slits 8 are formed longitudinally with respect to the reinforcing elements on the end wall members, and the slits 9 are formed transversely with respect to said reinforcing elements. It will be noted that the slits 8 and 9, of each end wall member, are formed between the reinforcing elements 6 and 7 which extend across the box. By forming each end wall member in this manner, I also produce comparatively short reinforcing elements 11 which extend from the slits 9 to the side edges of the blank.

In folding the box blank to produce the structure shown in Fig. IX, the extended portion of each end wall member is folded several times. The reinforcing element 5, at the outer edge of end wall C, is folded onto the reinforcing element 6; both of these elements are then folded onto the comparatively short reinforcing elements 11. The folded elements 5, 6 and 11 are then folded onto the reinforcing elements 7, and at this time the reinforcing elements occupy the position shown in Figs. II and VI, or as shown in Fig. IV. Before folding the reinforcing elements into the box, the side wall members are folded so that their extensions 3 will engage the end walls of the box, as shown in Figs. IV or IX. The reinforcing elements are then folded to overlap the side wall extensions 3, as shown in Figs. V or IX. Thereafter the different elements are secured together by fastening devices 12 which pass through the fastening flaps 10 and also

through side wall extensions 3 and end wall members C. The parts then occupy the position shown in Fig. IX, and they may be readily folded to the position shown in Fig. 5 V by folding the side and end wall sections upwardly, and then placing the curved edges 3' between the reinforcing elements and the end wall members. It will be noted that the reinforcing elements are secured by the 10 fastening flaps 10, and that the end portions of said reinforcing elements may be forced away from the wall members C so as to permit the curved edges 3' to be inserted between said wall members and reinforcing 15 elements, as indicated in Fig. V.

By forming each end wall member as shown most clearly in Fig. I, I produce three reinforcing elements which extend entirely across the box, and also produce two comparatively short reinforcing elements 11 which extend partially across the box, at the same time producing a fastening flap 10 adapted to secure all of the reinforcing elements after they have been folded to 20 operate with each other. Heretofore, boxes of this kind have been provided with end wall members having their outer edges folded for the purpose of reinforcing the box, and owing to the inefficiency of such reinforcing elements it has been a common practice to insert a long strip of wood into the 25 upper margins of such end walls for the 30

purpose of providing the necessary reinforcement. My box is so formed that the reinforcing elements form an integral part 35 of the box blank; they may be readily folded to produce the desired reinforcement, and in this connection it is a decided advantage to secure all of the reinforcing elements by the fastening flaps 10 which extend from the 40 end wall sections so as to confine all of the reinforcing elements in their folded condition.

I claim:—

A paper box having a bottom wall member, side wall members, and end wall members, said side wall members being provided with foldable extensions which engage the end wall members, the outer marginal portion of each end wall member being folded 50 to produce two reinforcing elements which extend across the box and two comparatively short reinforcing elements which lie between the first mentioned reinforcing elements, said marginal portion being slotted at 55 points between said comparatively short reinforcing elements and also, between the longer reinforcing elements, so as to produce a fastening flap which extends from said marginal portion, the foldable extensions of 60 the side wall members being fitted to said fastening flap, and means for securing said fastening flap and foldable extensions.

WM. J. BURT.
